UNITED STATES PATENT OFFICE.

CHARLES THOMAE, OF ATTLEBORO, MASSACHUSETTS, ASSIGNOR TO THE THOMAE COMPANY, OF ATTLEBORO, MASSACHUSETTS.

HOLDER FOR MATCHES.

1,362,371.

Specification of Letters Patent. Patented Dec. 14, 1920.

Application filed July 24, 1920. Serial No. 398,676.

To all whom it may concern:

Be it known that I, CHARLES THOMAE, a citizen of the United States, residing in the city of Attleboro, county of Bristol, and 5 Commonwealth of Massachusetts, have invented certain new and useful Improvements in Holders for Matches, of which the following is a specification, reference being had to the accompanying drawings, forming part 10 thereof.

My invention relates to holders for matches, particularly to holders for safety match folders.

In the accompanying drawings Figure I 15 is a view of the holder in front elevation. Fig. II is a view in rear elevation. Fig. III is a sectional view of Fig. I taken in the plane X—X Y—Y. Fig. IV is a sectional view of Fig. II taken in the plane 20 X'—X' Y'—Y'. Fig. V is a perspective view of the holder with the front removed and a portion of the paper match folder therein torn away.

Like characters denote like parts in all 25 the figures.

My invention is a simple device, both useful and ornamental, for holding safety match folders and it is so constructed that each match can be removed and ignited 30 without removing the folder entirely from the holder. The article is simple to manufacture, it being stamped from a single piece of metal and then bent into shape.

My new holder consists of a case having 35 a front A, a back B and sides C, the ends being entirely open. Across the bottom of the front A I provide an opening D which will expose the friction surface of the match folder when inserted in the case. Upon 40 the back B, I provide a spring finger E which is adjusted to retain the said folder in its proper place within the case. The back B is recessed at the bottom to expose a portion of the folder so that the same can 45 be easily pushed up through the case and

cause the matches to project from the top thereof. On the sides C, I place smaller spring fingers whose function is to engage the loop in the bottom of the folder when it is being thus pushed up, thereby forming a stop to prevent the entire removal thereof in that direction.

In using this holder, a package of matches is inserted in the top of the case, forced by the small spring fingers in the 50 sides, and pushed on downward into the case until it comes into firm frictional contact with the large spring finger in the back where it will be held until optionally released for use. The recessed portion of the 55 back B forms a convenient place from which the package can be pushed up until the folder is exposed from the top of the case sufficiently to detach the matches therefrom. The force used in detaching the 60 matches does not pull the package entirely from the case because movement in that direction is limited by the operation of the stop device above described. After a match 65 has been detached, the folder is pushed back 70 into the case and the friction surface thereof will then be exposed through the slot D where the match can be ignited.

The surface of the case is adapted to receive a varied ornamental treatment.

My claim is:

A case stamped from a single piece of metal to form a front, having a slot near the base; a back, provided with a recessed portion at the base; a spring finger stamped 80 from said back and bent inwardly; sides; grips stamped from said sides and bent inwardly.

In testimony whereof I hereunto affix my signature in the presence of two witnesses 85 this nineteenth day of July, A. D. 1920.

CHARLES THOMAE.

Witnessses:

JAMES L. BRIGGS,
CHAS. H. FRADD.
